UNITED STATES PATENT OFFICE.

JOSEPH A. MUIR, OF SMITHBORO, ILLINOIS.

SIGNAL FOR MINE-RAILWAYS.

1,274,072.

Specification of Letters Patent. Patented July 30, 1918.

Application filed March 23, 1916. Serial No. 86,129.

To all whom it may concern:

Be it known that I, JOSEPH A. MUIR, a citizen of the United States, residing at Smithboro, in the county of Bond and State 5 of Illinois, have invented a new and useful Signal for Mine-Railways, of which the following is a specification.

The device forming the subject matter of this application is a signal system adapted 10 to be employed primarily but not exclusively on railways in a mine.

The invention contemplates that the signal system shall be used in connection with a main track having branches or sidings, the 15 sidings leading into cross-entries in the mine. The system is actuated by a series of members located adjacent the tracks and adapted to be moved by the wheel of a passing car. It is the object of the invention to 20 provide novel means for actuating signals along the sidings and along the main track, by cars moving along the sidings and along the main track, in a manner which can be best comprehended when the construction 25 of the invention and its operation are thoroughly understood.

With the above and other objects in view which will appear as the description proceeds, the invention resides in the combination 30 and arrangement of parts and in the details of construction hereinafter described and claimed, it being understood that changes in the precise embodiment of the invention herein disclosed can be made without departing from the spirit of the invention. 35

In the accompanying drawing:

Figure 1 is a diagram illustrating the present signal system;

Fig. 2 is an elevation showing one of the wheel actuated members;

Figs. 3, 4 and 5 are transverse sections showing the means for mounting the wheel actuated member;

Fig. 6 is an elevation showing one of the wheel actuated members in operative relation to the rail;

Fig. 7 is an elevation showing one of the signal boxes;

Fig. 8 is a section of the signal box;

Fig. 9 is a perspective showing one of the rotatable shafts and its arms.

Fig. 10 is a side elevation showing a slight modification of the invention; and

Fig. 11 is a fragmental cross section 55 wherein the structure 10 is viewed edgewise for the most part.

In the accompanying drawings, and referring particularly to Fig. 1 there appears a main track denoted generally by the numeral 1 and embodying rails 2 and 3. Branching off from the main track 1 is a siding 4 embodying rails 5 and 6. Branching off from the main track 1 in a direction opposite to the siding 4 is a siding 7 comprising rails 8 and 9.

For the actuation of the signals to be described hereinafter, a plurality of duplicated structures are provided, these structures being located along the main track 1 70 and along the sidings 4 and 7. One of these structures will be described in detail, and thereafter the description will be shortened when one of the structures in question is alluded to.

Mounted on the under side of the rail 2 in advance of the siding 4 is a bearing 10, a similar bearing 11 being mounted on the rail 3. In the bearings 10 and 11 is mounted for rocking movement a shaft 12 extended 80 transversely of the main track 1 and located in advance of the siding 4. The shaft 12 is provided with an upstanding crank arm 14. Mounted on the rail 3 are hangers 15 each comprising a loop-shaped extension 16, the 85 extensions 16 supporting shafts 17. Mounted to swing on the shafts 17 are upright links 18, the upper ends of which are pivoted to a wheel actuated member or bar 19 disposed close to the rail 3 and preferably 90 beveled or inclined at its ends, the construction being such that when a wheel of a vehicle or car traverses the rail 3, the bar 19 will be depressed. The upper end of the crank arm 14 on the shaft 12 is pivoted to 95 the bar 19 intermediate the ends of the bar and consequently, when the bar 19 is moved endwise in one direction or the other, the shaft 12 will be rocked in its bearings. One end of the shaft 12 is provided with a fixed 100

upstanding arm 20 and with a fixed depending arm 21. Oppositely extended retractile springs 22 are provided, the inner ends of these springs being connected with the up- 5 per end of the arm 20 and the outer ends of the springs being connected as shown at 23 to a fixed support of some sort which may be the rail 3. The springs 22 serve to assist in rotating the shaft 12 and, through the me- 10 dium of the upstanding crank arm 14, aid in elevating the bar 19, when the latter is being reset to wheel engaging position.

The springs 22, and similar springs herein- 15 after described are not sufficiently strong to return the signals together with their connected operating mechanisms to safety-indicating position, on account of friction and on account of the weight of various moving parts. The signals and their operating 20 mechanisms will be described in detail as the description progresses.

The structure above described is duplicated at various points through the signal system, and hereinafter, allusion will be 25 made merely to the bar, represented by the bar 19, the shaft, such as the shaft 12, and the arms, as, for instance, the arms 20 and 21, it being understood that the structural details hereinbefore described are retained.

30 Disposed adjacent the siding 4 is a support 24 carrying a casing 25 adapted to contain a lamp 26 shown in Fig. 8. Signals or slides 27 and 28 are mounted to reciprocate in the casing 25, the slides 27 and 28 being 35 provided with plates 29 which preferably show red. It will now be obvious that if either of the slides 27 and 28 is pushed inwardly with respect to the casing 25, a car coming down the siding 4 in the direction 40 of the arrow F will encounter a red or danger signal.

Located opposite to the siding 4 is a casing 31, constructed like the casing 25, but provided with a single slide 32 of the sort 45 hereinbefore described.

Disposed adjacent the siding 7 is a casing 33 which, like the casing 25, carries two slides 34 and 35. The numeral 36 indicates a shaft, like the shaft 12, disposed trans- 50 versely of the siding 4, and adapted to be rocked by a wheel actuated bar 37, like the bar 19. The shaft 36 is provided with an upstanding arm 38 and with a depending arm 39. A shaft 40 is mounted to rock trans- 55 versely of the track 1 and is controlled by a wheel actuated bar 41, the shaft 40 having an upstanding arm 42 and a depending arm 43. Another shaft 44 is disposed trans- versely of the track 1 and is mounted to 60 rock, the shaft 44 being controlled by a wheel actuated bar 45. The shaft 44 is supplied with an upstanding arm 46 and with a depending arm 47. A shaft 48 is disposed transversely of the main track 1 near the

siding 7 and is rocked by a wheel actuated bar 49. The shaft 48 is provided with an up- 65 standing arm 50 and with a depending arm 51. Arranged transversely of the siding 7 is a shaft 72 adapted to be rocked by a wheel actuated bar 73. The shaft 72 is supplied 70 with an upstanding arm 74 and with a depending arm 75.

A vertical shaft 52 is mounted to rotate adjacent the casing 25, the shaft being pro- 75 vided with oppositely projecting arms 53 and 54, and with a forwardly presented arm 55. The shaft 52 and its arms, constitute, in effect, as will be manifest when the de- 80 scription is proceeded with, a three-armed lever. A vertical shaft 59 is mounted near the casing 25, the shaft 59 being provided with oppositely extended arms 60 and 61 and with a rearwardly projecting arm 62. Disposed near the casing 31 is a vertical shaft 56 having angularly disposed arms 57 85 and 58. Arranged near the signal casing 33 of the siding 7 is a vertical shaft 63 pro- 90 vided with oppositely projecting arms 64 and 65 and with an arm 66 which extends toward the main track 1. A vertical shaft 67 is located near the signal casing 33 and is provided with oppositely projecting arms 68 and 69, and with a rearwardly projecting arm 70.

Located adjacent the main track 1 near to the siding 4 is a bell crank 71 having angularly disposed arms 77 and 78. Located near to the bell crank 71 is a bell crank 79 having arms 80 and 81. The arms 77 and 81 of the bell cranks 71 and 79 project in a common 100 direction, whereas the arms 78 and 80 of the bell cranks project in opposite directions. Located near to the bell crank 79 is T-lever 82 comprising oppositely extended arms 83 and 84, and an arm 85 which projects in the same direction as the arms 81 and 77 of the bell cranks. Located near to the T-lever 82 is a T-lever 86 including arms 87 and 88 and a shank or arm 89 projecting in the same direction as the shank or arm 85 of the 105 T-lever 82. Disposed near the siding 7 is a bell crank 90 comprising arms 91 and 92. The numeral 93 designates a bell crank located near to the bell crank 90 and including arms 94 and 95. The arms 92 and 95 of the 110 bell cranks 90 and 93 project in a common direction, the arms 94 and 91 of the bell cranks projecting in opposite directions. The numeral 96 designates a T-lever includ- 115 ing oppositely projecting arms 97 and 98 and a shank 99. A T-lever 100 is shown, the T-lever including oppositely projecting arms 101 and 102 and a shank 103, the shank 103 of the T-lever 100 extending in the same 120 general direction as the shank 99 of the T- lever 96. The numeral 104 denotes a lever of the first order fulcrumed intermediate its ends as shown at 105 and mounted to swing 125

in a horizontal plane, the lever 104 being located between the T-lever 100 and the shaft 48.

A rigid connection 106 unites the arm 55 of the vertical shaft 52 with the signal slide 27 of the casing 25. A rigid connection 107 unites the arm 62 of the vertical shaft 59 with the signal slide 28 of the casing 25. A rigid connection 108 unites the arm 58 of the vertical shaft 56 with the slide or signal 32 of the casing 1. A rigid connection 109 unites the arm 70 of the vertical shaft 67 with the slide 34 of the casing 33. A rigid connection 110 unites the arm 66 of the vertical shaft 63 to the slide 35 of the casing 33. Although these various connections have been described as rigid, it is to be understood that they are pivoted to the parts wherewith they coact.

20 The invention includes a plurality of flexible elements which will now be described. These flexible elements may be fashioned in any desired manner, but to simplify the description, it will be presupposed that they 25 are wires, it being understood that in using the word wire no other suitable form of connection is excluded.

A wire 111 connects the upstanding arm 20 of the shaft 12 with the arm 57 of the 30 upright shaft 56 which is located adjacent the signal casing 31. A wire 112 unites the upstanding arm 20 of the shaft 12 with the shank 85 of the T-lever 82. A wire 114 unites the depending arm 21 of the shaft 12 35 with the shank 89 of the T-lever 86. A wire 116 unites the depending arm 39 of the shaft 36 on the siding 4 with the arm 80 of the bell crank 79. A wire 115 unites the upstanding arm 38 of the shaft 36 with the arm 78 of the bell crank 71. A wire 117 unites the arm 57 of the vertical shaft 56 with the arm 81 of the bell crank 79. A wire 118 unites the arm 77 of the bell crank 71 with the arm 95 of the bell crank 93. A wire 119 45 unites the arm 81 of the bell crank 79 with the arm 92 of the bell crank 90. A wire 120 unites the depending arm 43 of the shaft 40 with the shank 85 of the T-lever 82. A wire 121 unites the upstanding arm 42 of the 50 shaft 40 with the shank 89 of the lever 86. A wire 122 unites the arm 83 of the T-lever 82 with the arm 54 of the vertical shaft 52 which is located adjacent the signal casing 25. A wire 123 unites the arm 53 of the 55 shaft 52 with the arm 84 of the T-lever 82. A wire 124 unites the arm 61 of the vertical shaft 59 with the arm 87 of the T-lever 86. A wire 125 unites the arm 60 of the vertical shaft 59 with the arm 88 of the T-lever 86. 60 A wire 126 unites the shank 89 of the T-lever 86 with the shank 103 of the T-lever 100. A wire 127 unites the upstanding arm 46 of the shaft 44 with the shank 99 of the T-lever 96. A wire 128 unites the depending arm 47 of

the shaft 44 with the shank 103 of the T-lever 100. A wire 129 unites with the arm 91 of the bell crank lever 90 with the depending arm 75 of the shaft 72. A wire 130 unites the upstanding arm 74 of the shaft 72 with the arm 94 of the bell crank lever 93. A wire 131 unites the arm 95 of the bell crank lever 93 with one end of the lever 104, which, it is to be recalled, is a lever of the first order. A wire 132 unites the other end of the lever 104 with the shank 103 of the T-lever 100. A wire 133 unites the upstanding arm 50 of the shaft 48 with the shank 103 of the T-lever 100. A wire 134 unites the depending arm 51 of the shaft 48 with the shank 99 of the T-lever 96. A wire 135 unites the arm 101 of the T-lever 100 with the arm 69 on the vertical shaft 67 located adjacent the signal casing 33. A wire 136 unites the arm 68 of the shaft 67 with the arm 102 of the T-lever 100. A wire 137 connects the arm 65 of the vertical shaft 63 which is located near to the casing 33, with the arm 98 of the T-lever 96. A wire 138 connects the arm 64 of the shaft 63 to the arm 97 of the T-lever 96.

90 The practical operation of the structure is as follows:—

Suppose that a car is moving along the main track 1 in the direction of the arrow A. The wheel of the car engages the bar 19 and rocks the shaft 12. The arm 21 pulls on the wire 114 and the T-lever 86 is swung by means of the arm 89, the arm 88 pulling on the wire 125 and the shaft 59 being rotated by means of the arm 60. The arm 62 on the shaft 59 through the medium of the rigid connection 107 advances the slide or signal 28 in the signal casing 25 so that a red light is shown against a car moving down the siding 4 in the direction of the arrow F. When the shank 89 of the T-lever 86 is swung as hereinbefore described by the action of the wire 114, a pull is exerted on the wire 126, the wire 126 swinging the T-lever 100 by means of the shank 103. The arm 102 of the T-lever 100 exerts a pull on the wire 36, and the wire 136 by means of the arm 68 rotates the shaft 67, the arm 70 of which exerts a thrust against the rigid connection 109, the connection 109 advancing the slide 34 so that a red light is shown against the car proceeding in the direction of the arrow D on the siding 7. Cars on both of the sidings 4 and 7 thus are confronted by danger or caution signals indicating that a car is proceeding along the main track 1.

Suppose that the car proceeds along the main track 1 in the direction of the arrow A until one wheel of the car engages the bar 41. Then the shaft 40 is rocked, and the arm 42 of the shaft 40 exerts a pull on the wire 121, the wire 121 swinging the T-

lever 86 by means of the shank 89. Thereupon, the arm 87 of the T-lever 86 exerts a pull on the wire 124, rotating the shaft 59 through the medium of the arm 61, the arm 5 62 on the shaft 59 exerting a pull on the connection 107, the connection 107 withdrawing or retracting the slide 28. Thereupon a white light is disclosed to a car proceeding in the direction of the arrow F 10 along the siding 4, thereby indicating that the car moving along the track 1 has passed the siding 4.

The car, moving along the main track 1 in the direction of the arrow A, engages the bar 45 and rocks the shaft 44. The arm 47 takes the slack out of the flexible element 128 but operates no signal, the flexible element 128 being a resetting wire for the bar 45.

20 Finally, the car, proceeding in the direction of the arrow A along the main track 1, operates the bar 49 which, in turn, rocks the shaft 48, the arm 50 of the shaft 48 pulling the wire 133. The wire 133 rocks the T-lever 100 by means of the shank 103, whereupon the arm 101 of the T-lever 100 exerts a pull on the wire 135, the wire 135 25 rotating the shaft 67 by means of the arm 69, whereupon the arm 70 will exert a pull upon the connection 109, the connection 109 exerting a pull upon the signal slide 34 and retracting it, thereby showing to a car proceeding in the direction of the arrow D along the siding 7, that the car moving on 30 the main track 1 in the direction of the arrow A has passed the siding 7.

Now let it be supposed that a car is moving along the main track 1 in the direction of the arrow B. The car coöperates with 40 the bar 49 and rocks the shaft 48. The arm 51 exerts a pull on the wire 134, and the wire 134 swings the T-lever 96 by means of the arm 99. The arm 98 of the T-lever 96 exerts a pull on the wire 137, the wire 137 45 rotating the shaft 63 through the medium of the arm 65. The arm 66 on the shaft 63 exerts a thrust against the connection 110 and the connection 110 advances the signal 35, thus showing red against the car moving in the direction of the arrow D on the track 7.

The car, moving along the track 1 in the direction of the arrow B coöperates with the bar 45 and rocks the shaft 44. The arm 55 46 on the shaft 44 exerts a pull on the wire 127, and the wire 127 swings the T-lever 96 by means of the shank 99. The arm 97 of the T-lever 96 exerts a pull on the wire 138 and rotates the shaft 63 by means of the 50 arm 64, the arm 66 on the shaft 63 retracting the signal 35 through the medium of the connection 110. A white light is now shown to a car moving in the direction of the arrow D, on the siding 7 and the opera-

tor of such a car is advised that the car 65 moving along the track 1 has passed the siding 7.

The car moving along the track 1 in the direction of the arrow B coöperates with the bar 41 and rocks the shaft 40. The arm 43 70 of the shaft 40 exerts a pull on the wire 120 and the wire 120 swings the T-lever 82 by means of the arm 85. The arm 83 of the T-lever 82 pulls on the wire 122 and the wire 122 rotates the shaft 52 by means of the arm 54. The arm 55 on the shaft 52 operates the signal 27, through the medium of the connection 106, indicating to a car proceeding in the direction of the arrow F along the siding 4, that a car moving along the track 80 1 in the direction of the arrow B is approaching the siding 4.

The car moving in the direction of the arrow B on the track 1 coöperates with the bar 19, rocking the shaft 12. The arm 20 85 on the shaft 12 exerts a pull on the wire 112. The wire 112 swings the T-lever 82 by means of the arm 85. The arm 84 of the T-lever 82 exerts a pull on the wire 123 and the wire 123 rotates the shaft 52 through the medium 90 of the arm 53. The arm 55 of the shaft 52 exerts a pull on the connection 106 and the connection 106 retracts the slide or signal 27, thus indicating to a car moving in the direction of the arrow F along the siding 4, 95 that the car on the main track 1 and moving in the direction of the arrow B has passed the siding 4.

Now let it be supposed that a car is proceeding along the main track 1 in the direction of the arrow A. The bar 19 and parts associated therewith advance the signal 28 as before, showing red against a car moving in the direction of the arrow F along the siding 4. In the manner hereinbefore described, the slide 34 of the casing 33 is advanced to show red against a car coming in the direction of the arrow D along the siding 7. Suppose that the car proceeding in the direction of the arrow A along the 100 track 1 turns into the siding 4, in the direction of the arrow E. Then, the car engages the bar 37 and the latter rocks the shaft 36. The arm 38 of the shaft 36 exerts a pull on the wire 115 and the wire 115 swings the bell 115 crank lever 71 by means of the arm 78. The arm 77 of the bell crank lever 71 exerts a pull on the wire 118, and the wire 118, co-operating with the wire 131, swings the lever 104 on its fulcrum 105. The lever 104 105 exerts a pull on the wire 132. Thus the T-lever 100 is swung by means of the shank 103. The arm 101 of the T-lever 100 exerts a pull on the wire 135, the latter rotating the shaft 67 by means of the arm 69, the arm 70 120 on the shaft 67 exerting a pull on the connection 109, and the connection 109 retracting the slide or signal 34. It is now made

125

manifest to a car proceeding in the direction of the arrow D along the siding 7, that the main track 1 is clear.

When the T-lever 100 is swung in the manner hereinbefore set forth, the shank 103 of the T-lever 100 exerts a pull on the wire 126, the latter swinging the lever 86 by means of its shank 89, the arm 87 of the T-lever 86 exerting a pull on the wire 124, the wire 124 rotating the shaft 59 by means of the arm 61, the arm 62 on the shaft 59 exerting a pull on the connection 107, and the slide or signal 28 being retracted, it being recalled that the signal 28 was previously advanced by the car moving in the direction of the arrow A along the track 1, when the said car operated the bar 19 before the car had turned into the siding 4.

Suppose that a car moving along the track 1 in the direction of the arrow A passes by the siding 4. This car first actuates the bar 19 and the shaft 12 and thus the signal 28 is advanced, and the signal 34 is advanced also. The car, moving in the direction of the arrow A along the track 1 ultimately operates the bar 41, the bar 41 rotates the shaft 40 and the arm 42 pulls on the wire 121, the T-lever 86 being tilted by the arm 89, the arm 87 of the T-lever exerts a pull on the wire 124, the shaft 59 being rotated by the arm 61, and the arm 62 retracting the slide or signal 28 through the medium of the connection 107. It is now evident, as before to a car proceeding in the direction of the arrow F along the siding 4, that the main track 1 is clear, to the left of the siding 4.

The car, moving in the direction of the arrow A along the track 1, operates the shaft 44 through the medium of the bar 45. The arm 47 on the shaft 44 takes the slack out of the wire 128, the signal 34 being already in an advanced position with respect to the casing 33. If the car moving on the main track 1 in the direction of the arrow A turns into the siding 7 and moves along the siding 7 in the direction of the arrow C, the bar 73 imparts rocking movement to the shaft 72 and the arm 74 on the shaft 72 exerts a pull on the wire 130 and tilts the bell crank lever 93 by means of the arm 94. The arm 95 of the lever 93 exerts a pull on the wire 131, and the wire 131 tilts the lever 104 on its fulcrum 105. A pull is thus exerted on the wire 132 and the wire 132 swings the lever 100 by means of the shank 103. The arm 101 of the T-lever 100 exerts a pull on the wire 135 and thus the shaft 67 is rotated by means of the arm 69. The arm 70 of the shaft 67 exerts a pull on the connection 109 and the slide 34 is retracted.

Suppose that a car is coming out of the siding 4 in the direction of the arrow F.

The car actuates the bar 37, rocking the shaft 36. The arm 39 of the shaft 36 pulls on the wire 116 and tilts the bell crank 79 by means of the arm 80. The arm 81 of the bell crank 79 pulls on the wire 117 as shown by the arrow in Fig. 1 and the wire 117 rotates the shaft 56 by means of the arm 57. The arm 58 of the shaft 56 advances the slide 32 through the medium of the connection 108.

From the signal casing 31 there is exhibited a red light, indicating to a car on the main track 1 that a car is coming out of one of the sidings.

Let it be supposed that the car, after leaving the siding 4 moves along the main track 1 in the direction of the arrow B. The car then operates the bar 19 and rotates the shaft 12. The arm 20 on the shaft 12 exerts a pull on the wire 111, as shown by the arrow in Fig. 1, and the shaft 56 is rotated by means of the arm 57. The arm 58 on the shaft 56 exerts a pull on the connection 108, so that the signal slide 32 of the casing 31 is retracted, to show a white light.

Suppose that a car is coming out of the siding 7 in the direction of the arrow D. The car operates the shaft 72 by means of the bar 73 and the arm 75 on the shaft 72 exerts a pull on the wire 129, the wire 129 operating the bell crank lever 90 by means of the arm 91. The arm 92 of the bell crank lever 90 exerts a pull on the wire 119, the wire 119 exerts a pull on the wire 117, the wire 117 rotating the shaft 56 by means of the arm 57, the arm 58 on the shaft 56 advancing the slide 32 by means of the connection 108 thus showing red at the signal casing 31 to a car moving along the main track 1 and indicating to such a car that another car is moving out of one of the sidings.

If the car on the siding 7, moving in the direction of the arrow D, passes out onto the main track 1 and traverses the main track 1 in the direction of the arrow B, then the car rotates the shaft 44 through the medium of the bar 45. The arm 46 on the shaft 44 exerts a pull upon the wire 127, the wire 127 exerts a pull on the wire 134, the arms 51 and 50 are rocked, the arm 50 pulling on the wire 133, the wire 133 pulling the wire 126, the wire 126 pulling the wire 114, the wire 114 rocking the arms 21 and 20 on the shaft 12, the arm 20 exerting a pull upon the wire 111, the shaft 56 being rotated by means of the arm 57 and the arm 58 on the shaft 56 exerting a pull on the connection 108 which, in its turn will retract the signal slide 32.

By way of résumé it may be stated that when a car is moving in the direction of the arrow A on the track 1, the bar 19 first moves the signals 28 and 34 to danger indi-

cating position; the bar 41 then moves the signal 28 to safety indicating position and finally the bar 49 moves the signal 34 to safety indicating position.

- 5 When the car is moving in the direction of the arrow B along the main track 1, the bar 49 moves the signal 35 to danger indicating position, the bar 45 moves the signal 35 to safety indicating position, the bar 41 10 moves the signal 27 to danger indicating position, and the bar 19 moves the signal 27 to safety indicating position.

Before the car enters the siding 4, the bar 19 will throw the signals 28 and 34 to danger indicating positions, and after the car is in the siding 4, the bar 37 moves the signals 28 and 34 to safety indicating positions.

As the car moves along the main track 1 20 in the direction of the arrow A, the bar 19 moves the signals 28 and 34 to danger indicating positions, the bar 41 moves the signal 28 to safety indicating position, and when the car enters the siding 7, the bar 73 25 moves the signal 34 to safety indicating position.

When the car moves out of the siding 4 onto the main track, the bar 37 throws the signal 32 to danger indicating position, and 30 after the car is on the main track, the bar 19 moves the signal 32 to safety indicating position.

When the car moves out of the siding 7 onto the main track, the car, through the 35 medium of the bar 73, throws the signal 32 to danger indicating position, and after the car is on the main track, the bar 45 throws the signal 32 to safety indicating position.

For convenience in claiming the invention, the same may be described briefly as comprising a main track 4, a first car actuated member 19 on the main track, a second car actuated member 49 on the main track, a first siding 4 and a second siding 7 45 branching from the main track between the car actuated members 19 and 49, a third car actuated member 41 located on the main track between the sidings, a fourth car actuated member 45 located on the main track 50 between the sidings, a first signal 28 on the first siding 4, a second signal 27 on the first siding 4, a first signal 34 on the second siding 7, and a second signal 35 on the second siding 7.

55 In Figs. 10 and 11, a slight modification of the invention is shown. In the said figures, the rail appears at 276 and carries a bearing 277 in which is journaled a shaft 278 corresponding to the shafts 12, 36, 40, 60 44, 48 and 72. The shaft 278 is provided with an arm 279 corresponding, for instance, to the arm 20. The numeral 280 indicates an arm corresponding to the arm 21, the arm 280 being pivoted as shown at

281 to the bracket 282 on the rail 276. At 65 283 there appears a diagonal link, the upper end of which is pivoted at 284 to the arm 279, the lower end of the link 283 being pivoted as shown at 285 to the arm 280 below the pivotal mounting 281. A casual 70 inspection of Fig. 10 will make it evident that the functions of the arms 279 and 280 are the same as those of the arms 20 and 21, it being possible to substitute the structure shown in Fig. 10 for the structure 75 shown at 20 and 21, and elsewhere in Fig. 1, without departing from the spirit of the invention and without jeopardizing its utility. The specific advantage attendant upon the use of the structure shown in Fig. 10 is that 80 it permits the actuating wires, of which the wires 112 and 114 may be taken as typical, to be elevated. The parts 18, 14 and 19 are used in connection with this form of the invention.

Having thus described the invention, what is claimed is:—

1. In a railway signal system, a main track; first, second, third and fourth car actuated members on the main track; a first siding branching from the main track between the first and third car actuated members; a second siding branching from the main track between the second and fourth car actuated members; a signal on the first 90 siding; a first screen and a second screen movable with respect to said signal; a signal on the second siding; a third screen and a fourth screen movable with respect to the last specified signal; a mechanical means 95 connecting the first car actuated member with the second screen and with the third screen to advance the same; a mechanical means connecting the third car actuated member with the second screen to retract the latter; a mechanical means connecting the second car actuated member with the third screen to retract the same; a mechanical means connecting the second car actuated member with the fourth screen to advance 100 the same; a mechanical means connecting the fourth car actuated member with the fourth screen to retract the latter; a mechanical means connecting the third car actuated member with the first screen to advance 105 the latter; a mechanical means connecting the first car actuated member with the first screen to retract the latter; a fifth car actuated member on the first siding; a sixth car actuated member on the second 110 siding; mechanical connections between the fifth car actuated member and the second and third screens to retract the same; and a mechanical connection between the sixth car actuated member and the third screen 115 to retract the same.

2. A railway signal system constructed in accordance with claim 1, in combination

with a third signal located adjacent the juncture of the first siding and the main track; a single screen movable with respect to the third signal; a mechanical means connecting the fifth car actuated member with the single screen to advance the latter; a mechanical means connecting the first car actuated member with the single screen to retract the latter; mechanical means connecting the sixth car actuated member with the single screen to advance the latter; and

mechanical means connecting the fourth car actuated member with the single screen to retract the latter.

In testimony that I claim the foregoing 15 as my own, I have hereto affixed my signature in the presence of two witnesses.

JOSEPH A. MUIR.
